UNITED STATES PATENT OFFICE

DAVID H. CROSSER, OF CHICAGO, ILLINOIS, ASSIGNOR TO R. E. GEBHARDT COMPANY,
A CORPORATION OF ILLINOIS

CANDLESTICK

Application filed December 21, 1931. Serial No. 582,247.

The present invention relates to candle sticks or holders and has for its object to produce a simple and inexpensive device which will make it appear that the candle is rising from a mass of foliage, flowers or the like.

In the form which my invention will most commonly take, it will constitute a portable candle stick or holder and, therefore, the 10 present invention may be said to have for its object to produce a simple and inexpensive device of this kind.

The various features of novelty whereby my invention is characterized will herein- 15 after be pointed out with particularity in the claims; but, for a full understanding of my invention and of its objects and advantages, reference may be had to the following detailed description taken in connection with the accompanying drawing, wherein:

Figure 1 is a top plan view of the device embodying the present invention; Fig. 2 is a section, on a larger scale, taken on line 2—2 of Fig. 1; Fig. 3 is a section on line 3—3 25 of Fig. 2, all of the ornamental devices except the supporting stems therefor being omitted; and Fig. 4 is a vertical section through a modified form of device, shown applied to an electric light fixture of the 30 candle type.

Referring to Figs. 1, 2 and 3 of the drawing, 1 represents a base which may be simply a cardboard disk. Rising from the center of the base is a suitable socket 2 for receiving 35 and holding a candle. This socket is so formed, or is composed of such material that pins or wires may be thrust into the side walls through the upper ends of the latter. In the arrangement shown, the socket is 40 composed of three concentric layers, the inner layer 3 being simply a plain paper tube, and the outer layer 4 being also a plain tube; whereas the intermediate layer 5 is a corrugated sheet of paper, the corrugations running lengthwise of the tube. The wall of the tube is, therefore, filled with vertical 45 passages into which wires or other slender elements may be inserted. The base with its 50 socket constitutes a low candle stick or a holder which is very cheap but not very at-

tractive in appearance. I, therefore, cover the holder proper with an ornamental or decorative skirt which is also cheap but at the same time very attractive in appearance. This skirt surrounds the socket and extends 55 downwardly and outwardly from the upper end thereof beyond the edges of the base so as effectively to conceal the base; the skirt being provided with wires or stems that are engaged in the vertical recesses or passages 60 in the cylindrical wall of the socket; whereby the skirt is centrally supported at the upper end of the socket and otherwise stands free of the candle stick or holder.

In the arrangement shown, the skirt is composed of leaves 6 and clusters of berries 7. The leaves and the berries are provided with wire stems 8 that are slipped down into the passages or channels in the cylindrical wall of the socket. Although the wires or stems 70 will be held in place frictionally, I prefer to apply a little adhesive to insure against accidental separation of the ornamental elements. Also, the socket may be secured to the base by means of adhesive, as indicated at 9 in Fig. 2. 75

It will be seen that the ornamental elements can be so proportioned and arranged as to imitate a flower, any desired design of foliage, or flowers, or a combination of foliage and flowers or berries.

A finish may be given to the upper end of the socket by the addition of a metal sleeve 10 fitted into the socket and flanged at its upper end, as indicated at 11, to overlie the raw upper edge of the cylindrical socket.

In the use of the device, it is set on a table or other support and a candle, indicated in broken lines at A in Fig. 2, is set into the socket. The leaves or other decorative elements forming the skirt are preferably shaped to produce a central cup or depression in the dome-like skirt. Then, with the candle in place, nothing indicating the presence of the holder proper is apparent, and the candle seems to rise from the center of a mass of leaves, flowers, sprays, berries or any combination thereof.

Therefore, since the artificial decorations, as well as the holder proper, can be made very cheaply, highly attractive, ornamental candle 100

sticks or holders can be produced at a very low cost.

If the base member of the device is omitted or removed, the socket, which is now an open-ended tube, may be slipped over a candle or an imitation candle B of an electric lighting fixture, as indicated in Fig. 4. The skirt, in this case, may be caused to hang down straighter than when it is required to cover 10 a broad base; thereby concealing the outer end of the supporting arm or bracket of the lighting fixture and so producing the effect of a candle rising from a mass of foliage or the like without other visible means of support.

While I have illustrated and described with particularity only a single preferred form of my invention, with a slight modification, I do not desire to be limited to the exact structural details thus illustrated and described; but intend to cover all forms and arrangements which come within the definitions of my invention constituting the appended claims.

I claim:

1. A socket adapted to hold a candle and a decorative skirt surrounding the socket, secured to the socket only at the upper end of the latter, and flaring outwardly and downwardly.

2. A socket adapted to hold a candle and a decorative skirt therefor in the form of leaves connected at their bases to the rim of the socket and hanging down beside the socket.

3. A candle stick comprising a base, a socket on the base, and an ornamental skirt secured to the upper end of the socket and flaring outwardly and downwardly to conceal both the socket and the base.

4. A candle stick including a base and a socket on the base, and an ornamental skirt concealing the socket and the base comprising artificial leaves fixed at their bases to the rim of the socket and flaring outwardly and downwardly.

5. A device of the character described, comprising a socket adapted to hold a candle, the walls of the socket being constructed and arranged to permit wires or the like to be inserted into the same through the rim of the socket, and a skirt surrounding the socket and including leaves having wire stems stuck into the socket through the rim.

6. A device of the character described, comprising a tubular member composed of a material easily penetrable through an end face of the tube by a wire or pin, and a decorative skirt surrounding the said member and including leaves having wire stems inserted in the walls of the tube through said end face.

7. A candle stick including a base and a socket adapted to hold a candle rising from the base, the socket being of a material easily

penetrable by a wire inserted lengthwise of the sides of the socket through the upper end, and an ornamental skirt surrounding the socket and extending from the upper end thereof outwardly and downwardly, to form 70 a cover for the base, said skirt including artificial leaves having wire stems penetrating the walls of the socket through the upper end.

8. A candle stick including a base and a socket adapted to hold a candle rising from 75 the base, the socket being of a material easily penetrable by a wire inserted lengthwise of the sides of the socket through the upper end, and an ornamental skirt surrounding the socket and extending from the upper end 80 thereof outwardly and downwardly, to form a cover for the base, said skirt having wire stems penetrating the walls of the socket from the upper end and constituting the supporting means for the skirt.

In testimony whereof, I sign this specification.

DAVID H. CROSSER.
